(57) **CLAIM**

The ornamental design for a one handed dispensing pouch, substantially as shown and described.

DESCRIPTION

FIG. 1 is a front perspective view of a one handed dispensing pouch in accordance with one form of the present invention; FIG. 2 is a top plan view of the one handed dispensing pouch of FIG. 1;

FIG. 3 is a front elevation view of the one handed dispensing pouch affixed to a pouch of FIG. 1;

FIG. 4 is a right side elevation view of the one handed dispensing pouch of FIG. 1;

FIG. 5 is a front perspective view of a one handed dispensing pouch in accordance with a second form of the present invention;

FIG. 6 is a top plan view of the one handed dispensing pouch of FIG. 5;

FIG. 7 is a front elevation view of the one handed dispensing pouch of FIG. 5;

FIG. 8 is a right side elevation view of the one handed dispensing pouch of FIG. 5;

FIG. 9 is a front perspective view of a one handed dispensing pouch in accordance with a third form of the present invention;

FIG. 10 is a top plan view of the one handed dispensing pouch of FIG. 9;

FIG. 11 is a front elevation view of the one handed dispensing pouch of FIG. 9;

FIG. 12 is a right side elevation view of the one handed dispensing pouch of FIG. 9;

FIG. 13 is a front perspective view of a one handed dispensing pouch in accordance with a fourth form of the present invention;

FIG. 14 is a top plan view of the one handed dispensing pouch of FIG. 13;

FIG. 15 is a front elevation view of the one handed dispensing pouch of FIG. 13; and,

(Continued)

FIG. 16 is a right side elevation view of the one handed dispensing pouch of FIG. 13.

In the drawings, the broken lines show portions of a one handed dispensing pouch that form no part of the claim.
